UNITED STATES PATENT OFFICE.

CHARLES WARWICK, OF VANCOUVER, BRITISH COLUMBIA, CANADA, ASSIGNOR TO
WILLIAM R. RICHARDSON, OF VANCOUVER, CANADA.

DOMESTIC OIL BURNER.

Application filed May 23, 1921. Serial No. 471,870.

To all whom it may concern:

Be it known that I, CHARLES WARWICK, citizen of the Dominion of Canada, residing at Vancouver, in the Province of British Columbia, Canada, have invented certain new and useful Improvements in Domestic Oil Burners, of which the following is a specification.

This invention relates to an oil vaporizer and burner which has been particularly designed for application to domestic use and to provide a safe and economical means for using a liquid fuel, such as coal oil.

The invention is particularly described in the following specification, reference being made to the drawings by which it is accompanied, in which:

Fig. 1 is a centrally vertically longitudinal section.

Fig. 2 is a cross section on the line 2—2 in Fig. 1.

Figure 3 is a cross section of a modified form of the invention.

Figs. 4 and 5 are detail views of the gauze filling of the vaporizing tube.

In these drawings 2 represents an elongated, hollow chamber into which the vaporized oil and air are delivered in a condition for combustion. In cross section, this chamber is as shown in Fig. 3, the sides rounding to the top with a medial channel 3 between the two ridges so formed. One end of this chamber 2 is closed by an end plate 4 secured by screws or studs, and to the opposite end is attached in a similar manner, a mixing chamber 5. The inside of this chamber 2 is lined with a heat non-conducting cement, or if practical the entire chamber may be made of such material.

Extending along the entire length of the burner chamber 2 immediately over the medial channel 3 is an oil vaporizing tube 6, the discharge nozzle 7 of which is inserted through an aperture into the mixing chamber 5 and the other end is supported in an aperture in the end plate 4. To this end an oil fuel service pipe is connected at 8. The tube 6 for about three-quarters of its length is packed with short rolls 10 of fine mesh wire gauze, and the remainder toward the discharge tip 7 is packed closely with washers 9 of fine wire gauze approximately fifty mesh.

The nozzle tip 7 has a fine axial aperture through which the vaporized oil is delivered

into the mixing chamber, and adjacent this tip 7 three ports deliver a supply of air to be mixed with the oil vapour as delivered through it. The port 11 of one of these air delivery ducts is located immediately above the delivery nozzle 7 and the other two 12 are on the opposite sides and derive their air from below, as shown in Fig. 2.

In practical alignment with the delivery nozzle 7 is a duct 13, which, see Fig. 1, is curved downward and connects to the cavity of the burner chamber 2.

The upper side of the burner chamber 2 may, as shown in Fig. 1, have a series of transverse slits 14 through which the gas and air issue for combustion, or as shown in Fig. 3, may have a series of small perforated burner tips 15 of lava inserted at intervals apart, one row of smaller size being arranged along each inner side of the medial channel 3 and directed toward the axis of the vaporizing tube 6.

In operation, the body of the burner complete may be supported within the fire-box of an ordinary kitchen stove and the oil fuel is delivered under pressure through a capillary tube connected to the end 8 of the vaporizing chamber. Initially the burner is primed with a liquid hydrocarbon in the channel 3 and the heat of this priming flame vaporizes the oil delivered to the tube at 8 as it slowly percolates along the tube through the wire gauze rolls and washers 10 and 9. This filling of the tube 6 being of metal (a conducting material) enables the heat directed on the outside of the tube to be quickly conducted through it and brought intimately in contact with the finely divided oil as it percolates through the filling. This is regarded as one of the important features of the device and differentiates it from those vaporizing tubes which are packed with asbestos fibre or the like non-conducting material.

The oil vapour being under pressure in the vaporizing tube rapidly expands when delivered therefrom through the fine axial aperture of the tip 7 and mixes freely with the air admitted through the ducts 11 and 12, and being directed forward into the duct 13 which connects with the cavity of the burner a continuous fresh supply of air is indrawn.

This combustible mixture of vaporized oil and air burns freely and completely as it

passes through the slits 14 of the burner, or where a wider spread of flame is required, through the burner tips 15.

The burner may be used without enclosure in the fire-box of a stove and if so used rods 16, shown in dot and dash lines in the drawing, are supported at 17 on the end plate 4 and mixing chamber 5 respectively, on which rods any article may be placed that require to be heated.

Having now particularly described my invention, I hereby declare that what I claim as new and desire to be protected in by Letters Patent, is:

15 An oil fuel burner, comprising in combination, an elongated chamber apertured along its upper side as a burner, a vaporizing tube disposed medially along the upper side of the burner chamber and parallel

therewith, said tube filled with a permeable heat conducting material, means for delivering oil fuel under pressure to one end of the vaporizing tube, means for delivering the vaporized oil through a fine aperture in the other end of the tube, a mixing chamber secured to the end of the burner chamber into which mixing chamber the end of the vaporizing tube is inserted, a duct delivering from adjacent the vaporizing tube end into the burner chamber, an air duct delivering from above into the mixing chamber adjacent the vaporizing tube end, and an air duct on each side opposite delivering into the mixing chamber adjacent the vaporizing tube end. 35

In testimony whereof I affix my signature.

CHARLES WARWICK.
